UNITED STATES PATENT OFFICE.

JOHN EWING, OF SAN FRANCISCO, CALIFORNIA.

DESIGN FOR A HORSESHOE-PAD.

SPECIFICATION forming part of **Design No. 33,691**, dated December 11, 1900.

Application filed November 6, 1900. Serial No. 35,680. Term of patent 7 years.

To all whom it may concern:

Be it known that I, JOHN EWING, a citizen of the United States, residing in the city and county of San Francisco, State of California, 5 have invented and produced a new and original Design for Horseshoe-Pads, of which the following is a specification, reference being had to the accompanying drawing, forming part thereof.

- 10 The figure is a perspective view of the pad. As shown in the drawing, the leading or material feature of my design consists of the segmental or crescent-shaped portion A, having a rear portion provided with divergent 15 angular ends. The crescent-shaped block

has a thin flat plate 2, with inner and outer edges curved. To the rear of the portion A extends the solid block 3, having curved walls and divergent angular ends 4, this block being substantially of the same thickness as the 20 crescent-shaped portion.

What I claim is—

The design for a horseshoe-pad as herein shown and described.

In witness whereof I have hereunto set my 25 hand.

JOHN EWING.
